TIRE

Michael A. Kolowski, Tallmadge, and Lance R. McKisick, Cuyahoga Falls, Ohio, assignors to The Goodyear Tire & Rubber Company, Akron, Ohio, a corporation of Ohio

Filed Sept. 18, 1967, Ser. No. 8,643

Term of patent 14 years

(Cl. D90—20)

The figure is a perspective view of a tire showing our new design, it being understood that the full line portion of the design is repeated throughout the circumference of the tire, the opposite side being substantially the same as that shown.

The dominant features of the design reside in the portions shown in full lines in the drawings.

We claim:

The ornamental design for a tire, substantially as shown and described.
